CLOCK CASING

Frederic H. Fisher, Syracuse, N. Y., assignor to
Crestwood Products Co. Inc., Syracuse, N. Y.,
a corporation of New York

Application April 6, 1950, Serial No. 9,013

Term of patent 3½ years

(Cl. D42—7)

To all whom it may concern:

Be it known that I, Frederic H. Fisher, a citizen of the United States, residing in Syracuse, county of Onondaga, and State of New York, have invented a new, original, and ornamental Design for a Clock Casing, of which the following is a specification, reference being had to the accompanying drawing, forming a part thereof, wherein:

The figure is a perspective view of a clock casing, showing my new design, the rear of the same being flat and plain.

I claim:

The ornamental design for a clock casing, substantially as shown and described.

FREDERIC H. FISHER.
